UNITED STATES PATENT OFFICE

117,739

DESIGN FOR AN END FRAME FOR CHAIRS, TABLES, OR THE LIKE

Carmon E. West, Sylvania, Ohio, assignor to The
Hetrick Manufacturing Company, Toledo,
Ohio, a corporation of Ohio

Application September 13, 1939, Serial No. 87,197

Term of patent 7 years

To all whom it may concern:

Be it known that I, Carmon E. West, a citizen of the United States and resident of Sylvania, Lucas County, Ohio, have invented a new, original, and ornamental Design for an End Frame for Chairs, Tables, or the Like, of which the following is a specification, reference being had to the accompanying drawing, forming a part thereof.

In the drawing:

Figure 1 is a perspective view of the end frame for chairs, tables, or the like showing my new design; and

Figure 2 is an end elevation of the end frame.

I claim:

The ornamental design for an end frame for chairs, tables, or the like, as shown.

CARMON E. WEST.
